COLLAR BEADING AND SHAPING MACHINE

Charles C. Greco, Bronxville, Patrick E. Ruffolo, East Rockaway, and Jacob M. Kessler, Brooklyn, N. Y.

Application November 13, 1951, Serial No. 256,094

5 Claims. (Cl. 223—2)

This invention relates to improvements in a collar beading and shaping machine and relates particularly to a machine of the character described comprising a collar forming means which is pivotally mounted upon a work table and adapted to receive a collar which is then pressed and formed into shape prior to its attachment to a garment.

An object of this invention is the provision therein of a collar forming means which is swingable about a horizontal axis, from a horizontal pressing position to a vertical collar attaching position.

A further object of this invention is the provision of means therein for vertically raising the forming means to a working height position in which position the collar to be processed could be readily attached.

A still further object of this invention is the provision therein of spring actuated locking means for maintaining the forming plate in its vertical position.

Another object of this invention is the inclusion therein of a forming means composed of a fixed end section, an adjustable end section and removable spacer strips or sections of various sizes adapted to be disposed between the adjustable section and fixed end section to extend the longitudinal length of the forming plate thereby adapting same to receive variously sized collars.

Yet another object of this invention is the provision therein of a swinging end section pivotally attached to the fixed section of the forming means and adapted to contract the extreme end portions of the forming means to permit the adjustment of a collar to same.

A still further object of this invention is the provision of an organization in which the constituent elements are so arranged structurally and functionally as to assure improved results with materials and members which may be manufactured at reasonable cost, may be easily assembled and which will be efficient in operation with minimum wear to the parts.

The best embodiment of the invention has been chosen for illustrative purposes, but this embodiment should be viewed as being illustrative only and not as limiting because obviously the invention is capable of other embodiments having revised details of construction, so long as they fall within the ambit of the appended claims.

The invention itself, however, both as to its organization and its method of operation, will best be understood from the following description of a specific embodiment when read in connection with the accompanying drawing, in which:

Fig. 1 is a plan view of the top of a work table upon which the collar forming means is attached.

Fig. 2 is a sectional elevation of same taken along line 2—2 of Fig. 1.

Fig. 3 is an elevational view, partly in section, and with parts broken away looking in the direction indicated by the arrow X in Fig. 1.

Fig. 4 is an enlarged fragmentary detail of a portion

2

of a forming means which will hereinafter be fully described and explained.

Fig. 5 is an end elevational view of Fig. 4 looking in the direction indicated by the arrow Y.

Fig. 6 is a fragmentary detail to be hereinafter explained, and

Fig. 7 is a sectional elevational view taken along line 7—7 of Fig. 4.

In the manufacture of garments for women's wear which include collars, the conventional practice is to construct the collar by stitching two collar shaped sections of material together along three outer edges with the unfinished side of the material upon the outside (an interlining, properly shaped, may be sewn with the collar shaped sections) and the whole then turned inside out bringing the finished surface of the material to the outside. The three sewn edges of the material will then present an uneven and probably lumpy shaped edge. This uneven edge must be smoothed out before the collar is attached to the garment. This smoothing out along the edges of the collar is termed, by the trade, beading and shaping the collar.

There are, at present in use, devices which bead and shape only the end portions of the collar. Such devices leave the central portion of the collar unbeaded and unshaped and requires additional pressing after the collar is removed from the beading sections.

In the invention which forms the subject matter of this application, a forming means is provided by the use of which the entire collar and edges may be beaded and shaped and eliminates the necessity of the additional processing described.

This invention consists essentially of a work table upon which there is mounted a vertically moving foot pedal operated frame to which there is pivotally attached a collar beading and shaping unit which includes sectional plates upon which a collar to be processed may be attached. The beading and shaping unit is provided with a pivotal end section which may be collapsed to shorten the distance between the tapered outer ends of the beading and shaping unit and permit the ready attachment of a collar.

Referring in detail to the parts in which similar reference numerals refer to similar parts, 11 designates the top of a worktable which is provided with legs 12, lower cross-bars 13 and an intermediate cross-bar 14. A supporting frame vertically slidable through the work table comprises a pair of upstanding bars 15 and 16 which engage through flanged bushings 17 and 18 respectively and are connected, at their lower ends, by a spanning plate 19. A lifting bar 20 is secured to and depends from the spanning plate 19 and engages the end 21 of a lever 22 which is pivoted to a supporting member 23. The supporting member 23 is securely mounted upon the intermediate cross-bar 14 and the outer end of the lever 22 is formed with a pedal 24 which may be depressed by the foot of an operator to raise the spanning bar 19 and its connected upstanding bars 15 and 16, respectively. Tubular boss formations 25 and 26 are secured to the upper ends of the upstanding bars 15 and 16, respectively.

The said tubular bosses 25 and 26 are secured to the upstanding rods 15 and 16 respectively, by means of pins 27 (Figs. 5 and 6) which engage through the upstanding bars and through the contracted stems 28 depending from each of said tubular bosses. A collar 29 is secured to the upstanding bars 15 and 16 by a pin 30 and is adapted to limit the downward movement of said upstanding bars. The dot and dash lines 11' in Figs. 5 and 6 indicate the level of the table top. A slotted holding plate 31 is pivotally connected to and extends from a tubular tongue formation 32 which is disposed

between the tubular bosses 25 and 26 and is held in place therebetween by a pin 33 thus pivoting the holding plate to the bosses 25 and 26.

The said holding plate 31 is formed throughout its length with a groove 34 and behind the groove 34 there is formed a slot 35 thereby forming an upper and lower wing 36 and 37 respectively. At one end of the said holding plate 31 and engaging in the groove 34 there is a fixed section 38 of a sectional forming plate, which fixed section is held in place by screws 39 or by any other suitable means. Adjoining the fixed section 38 there is a filler or spacer section 39 which removably engages within the groove 34 and adjoining the spacer 39 there is a large end section 40, removably engaging in the groove 34. The said sections, namely 38, 39 and 40, may be securely held in the groove 34 by thumb or wing headed screws 41 which engage freely through the upper wing 36 and are threaded into the lower wing 37 of the said slotted holding plate 31. The said slot 35 permits sufficient flexibility, when the wing screws 41 are screwed into the lower wing, to tighten same against the edges of the sections 38, 39 and 40 to hold them securely in place.

An end section 42, tapered along its outer edge, is pivotally attached to the fixed section 38 by a headed pin 43 which engages freely through an ear formation 44 (Figs. 4 and 5) upon the tapered section 42 and is threaded into the section 38. A spring 45 engages around the pin 43 and is disposed between the head of the pin 43 and the ear 44 upon the tapered section 42. The said spring 45 holds the tapered section 42 down to the level of and flush with the adjoining fixed section 38. The tapered section 42, however, may be raised against the urge of the spring 45 to ride over the upper surface of the fixed section 38, as indicated by the dot and dash lines in Fig. 7. The two contacting edges of the fixed section 38 and the tapered section 42 may be beveled as at 46 and 47 respectively, to permit the tapered section to slide up to the level of the top of the fixed section and turned inwardly as indicated by the dot and dash lines in Fig. 4. The purpose of the inward pivotal movement of the tapered section 42 over the fixed section 38 will presently be explained. A helical spring 46 secured at one end to an eye 47 upon the tapered section 42 and at its other end to an eyelet 48 secured upon the said slotted holding plate 31, functions to bias the tapered section 42 into its normal position as clearly shown in Figs. 1 and 4.

In Fig. 1 the fixed section 38, a spacer strip or section 39, the width of which is indicated by A, and the end section 40 are arranged in position to receive a collar which is outlined by the dot and dash lines 50. When, however, a shorter collar is to be placed in position for processing, the spacer plate, the width of which is indicated by the letter A, is removed and the end section 40 is moved into the position shown by the dot and dash lines D. By setting in place a wider spacer, the width of which is indicated by the letter B, the end section assumes the position indicated by the dot and dash line B'; and similarly when a wider spacer, indicated by the letter C, is inserted, the outer edge of the end section 40 assumes the position indicated by the dot and dash line C'. In this manner the apparatus may be adapted for processing collars of varying lengths.

As already noted, the collars are stitched along three edges leaving an open edge through which the form must pass. The open edge being shorter than the extreme outer edge of the collar, the pivotal tapered section 42 is turned upon and overlaps the fixed section 38, thus shortening the extreme outer edge and allowing the sections to pass through the shorter open edge of the collar. After the collar has been placed the pivotal tapered section 42 is moved back to its outermost position through the urge of the spring 46. When the collar is in place upon the said sections, the said holding plate

31 is turned down to its horizontal position against a conventional pressing pad 51, best shown in Fig. 2, whereupon the collar is processed by ironing the beaded edges down to a smooth and even finish. The collar may then be removed and subsequently attached to a garment.

Before placing the collar in position the said slotted holding plate 31 is turned to a vertical position as indicated by the dot and dash lines 52 in Fig. 2, in which position the said slotted holding plate is held by means of a round headed lock pin 53 (Fig. 6) which engages in an indentation 54 formed in the opposing end of the tubular tongue 32. The lock pin 53 slidably engages in a bore 55 formed in each of the tubular bosses 25 and 26 and is backed by a spring 56 which will urge the lock pin 53 into the indentation 54 when the said slotted holding plate is turned to the vertical position. After the first pressing of the collar the said slotted holding plate 31 may be turned to its opposite horizontal position (Fig. 2) and the collar ironed upon its other side. 20 A central cut out portion forming a pocket 56 is provided to receive the winged heads of the tightening screws 41 as shown in Fig. 2.

Pins may be provided in lieu of the tightening screws 39, in which case slots 57 (Fig. 4) may be provided in the fixed section 38 and the wing headed screws may then be used to securely tighten the fixed section in place.

We claim:

1. A collar beading and shaping machine comprising 30 a work table, a pressing pad thereon, a supporting frame upon and adapted to have vertical reciprocal movement through said table, the upper portion of the said supporting frame adapted to rise slightly above the work table and pressing pad, foot pedal means coating with the said supporting frame and adapted to impart vertical movement thereto, a slotted holding plate pivotally attached to and extending from the upper portion of the said supporting frame, the slot in the said slotted holding plate being formed by flange formations along the length of the said slotted holding plate, a forming plate seated within the slot of the said slotted holding plate and formed of a plurality of sections, the first section extending from one end of said forming plate to approximately the center of same, a second section comprising filler or spacer strips and a third section slightly less in width than the first mentioned section, the said first section having pivotally attached to its outer end a swinging end section, the outer or unattached periphery of said sections conforming in shape to a garment collar to be processed, said garment collar being held upon the said forming plate during processing.

2. A collar beading and shaping machine as set forth in claim 1, wherein the said first section of the said forming plate is fixed in the said slotted holding plate, 55 the said third section of the forming plate being adjustably attached to the said slotted holding plate, spacer strip sections removably mounted upon said slotted holding plate by wing headed tightening screws.

3. A collar beading and shaping machine as set forth in claim 1, including an end section pivotally attached to the said first section of the said forming plate for contracting the outer end of the said forming plate and a spring disposed between the said pivoted end section and the said slotted holding plate to urge said pivoted section to its normal outer position.

4. A collar beading and shaping machine as set forth in claim 1, wherein the said slotted holding plate is adapted to swing about its pivotal connection with the said supporting frame and a spring actuated lock-pin 70 upon the said supporting frame, the said lock-pin adapted to engage in an indentation upon the said slotted holding plate for holding said slotted holding plate and its pivotally attached forming plate in an upright vertical position.

5. A collar beading and shaping machine as set forth

in claim 2, wherein the said third section of the said forming plate may, by loosening the said wing headed tightening screws, be moved outwardly along the length of the forming plate and spacer strips disposed in the opening thus formed to thereby lengthen the said forming plate.
